(57) **CLAIM**

The ornamental design for a electronic shelf label adaptor, as shown and described.

DESCRIPTION

FIG. 1 is a front perspective view showing my new design for a electronic shelf label adaptor,

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

In FIGS. 1-5, the electronic shelf label adapter is shown broken away in the center to represent indeterminate length.
